UNITED STATES PATENT OFFICE.

AAGE JENSEN, OF LOS ANGELES, CALIFORNIA.

METHOD OF PASTEURIZING LIQUIDS.

Application filed February 2, 1926. Serial No. 85,471.

My invention relates to the treatment of liquids, for the removal therefrom of deleterious gases, said removal occurring while the liquid is being pasteurized or otherwise treated, and has for its objects to provide an improved method of accomplishing this purpose without destroying or materially changing the physical or chemical structure of the liquid, the apparatus involved being extremely simple and highly efficient.

An apparatus adapted to carry out my improved method, and hereinafter described and illustrated in the accompanying drawings, shows a form readily applicable to the treatment of milk or cream, in which harmful gases are known to be present. These gases may be the result of organic changes, or they may be the outcome of bacteria growth, caused by absorbed flavors or improper feeding of the dairy cattle. Much trouble is encountered from the latter, and it is a common objection in many sections of the country between seasons, when the cattle crave change in diet and feed on weedy plants. Undesirable flavors from other causes are known to be present in milk and cream practically the entire year through, and can be traced to the feeding of turnips, silo, kale, certain legumes, etc.

30 In the accompanying drawings:—

Figure 1 is a perspective view of a complete assembly including my improved pasteurizer.

Figure 2 is a central vertical sectional view of the pasteurizer and its operating parts.

35 Figure 3 is a detail perspective view of the exhaust rotor of said pasteurizer.

Figure 4 is a detail perspective view partly broken away of the pasteurizer.

Figure 5 is a horizontal sectional view, 40 taken on the line V—V of Figure 2.

Figure 6 is a detail view partly in section of the suction pump employed with the apparatus.

45 Figure 7 is a sectional view of the pasteurizer showing a slightly modified construction.

Similar numerals of reference denote corresponding parts in the several views.

In the said drawings, referring more particularly to Figure 1, the reference numeral 1 50 denotes a pipe for supplying the liquid to be treated, the same discharging into the upper tank 2 of a regenerator 3 of the general type disclosed in Letters Patent No. 1,073,989, 55 granted to me September 23, 1913, said liquid after passing through said regenerator dis-

charging into the lower tank 4 thereof, from which it is led by pipe 5 into the pasteurizer 6 hereinafter described, wherein it is treated for the removal of gases, and is discharged therefrom through pipe 7 into the lower end of the regenerator 3 up which it passes to impart its heat to the incoming liquid, and from which it is discharged through the pipe 8 to the cooler 9, from which leads a pipe 10 to 60 carry away the treated liquid.

Referring specifically to the pasteurizer 6, the same comprises a metal base 11 supported on legs 12, fastened to which is a cylindrical lining 13 which forms an integral part of a 70 heating jacket 14 constructed with a helical circulating channel 15. A circulating pump 16 is connected with suction pipe 17 and discharge pipe 18, which latter returns to the jacket 14 through connecting pipe 19. Disposed in discharge pipe 18 is a perforated steam pipe 20 having a controlling valve 21. Conveniently located at the upper portion of the jacket 14 is a pressure release valve 22 and a pressure gage 23, their function being to 75 control and record the pressure in the jacket 14, which in turn will reflect the temperature of the circulating medium used.

On top of the cylindrical lining 13 is mounted a cover 24 having an annular channel 25 merging into a discharge outlet 26 to which is attached the pipe 7 and in which is located a temperature recording device 28. In the center of the cover 24 is located a suitable packed bearing 29, while through the center of the 80 base 11 is projected a stationary pipe 30 extending upward within the pasteurizer to a suitable height to permit correct functioning. This pipe serves, first, as a vertical guide for the exhaust rotor, hereinafter described; and, 85 secondly, as a draw-off pipe connected to the suction pump 31, shown in detail in Figure 6, the same being driven by a suitable electric motor 32 and discharging through pipe 33. Formed centrally in the base 11, surrounding the pipe 30, is a chamber 34 into which the liquid to be treated is introduced by pipe 5, said pipe being controlled by a suitable 90 valve 35.

In Figure 3 I have shown in detail the exhaust rotor within the pasteurizer 6, which is constructed especially to withstand high speed and with attendant ability to develop pressure. The embodiment of the same embraces a hollow shaft 36 adapted to fit over the tube 30 and fastened to which are two or more cylindrical disks 37, said disks serv-

ing to carry vertical vanes 38 and also to confine the liquid being treated so as to prevent splashing in its passage through the pasteurizer. The bottom disk 37 is imperforate, and 5 is fitted with radial vanes 39 in order to secure a maximum centrifugal action on the liquid entering from the chamber 34 through the apertures 40, said vanes also serving to prevent the exhaust fan or pump 31 from 10 drawing out the liquid being treated. The remaining disks 37 are provided with apertures 41 to permit the free passage therethrough of gases in the liquid so that they may escape toward the exhaust outlet through 15 the pipe 30, as hereinafter described. That portion of the hollow shaft 36 which lies above the upper end of the pipe 30, is provided with a plurality of apertures 36' to provide communication between the interior of 20 the pasteurizer and said pipe 30. Said exhaust rotor is intended to be supported independently of the pasteurizer casing and to accomplish this I provide a combined overhead drive and support for the same carried by a 25 casting 42. Said drive comprises a drive shaft 43, connected to the hollow shaft 36 by intermediate shaft connections 44, 44', having suitable detachable joints 45, said shaft 43 having fixed thereto a pulley 46 and being 30 carried by suitable thrust bearing 46' designed to support the weight of the rotor and its parts. Running from said pulley 46 over idler pulleys 47 is a drive belt 48, extending 35 to a pulley 49 mounted on shaft 50 driven by a suitable electric motor 51. The circulating pump 16 is also driven by said shaft 50, as clearly shown in Figure 1.

The operation of my improved apparatus is as follows: The apparatus is cleaned and 40 steam then turned on through valve 21 and circulated through the jacket of the pasteurizer by means of the pump 16. As soon as the desired temperature has been obtained, the liquid to be treated is introduced through 45 pipe 5, its flow being regulated by the valve 35 therein. The speed of the suction pump 31 is gaged to produce a predetermined partial vacuum in the pipe 30, which at all times must balance with the pressure in the pasteurizer, 50 and also must be maintained in proper relation to the boiling pressure of the liquid being treated as the temperature of the same increases progressively. The liquid entering chamber 34 is discharged through apertures 55 40 into the interior of the pasteurizer 6, and is subjected, first, to the action of the radial vanes 39 to impart a centrifugal movement thereto, and as it rises in the pasteurizer, is subjected further to the action of the vertical 60 vanes 38, the latter rotating at high speed; the result being that the liquid gradually rises in the pasteurizer, but is kept away from the

hollow shaft 36, and is discharged first into the annular channel 25 and from thence into the discharge 26 and its pipe 7, whereby it is 65 conveyed to the lower end of the regenerator 3, as hereinbefore described.

It will be observed that while the liquid is being so treated in the pasteurizer 6, the deleterious gases are being withdrawn constantly by the centrifugal pump 31, acting on pipe 30 and discharging through pipe 33.

While the apparatus shown is adapted especially for the treatment of milk and cream, I do not wish to limit myself to the treatment 75 of these products, as there are many other liquids that can be treated beneficially by my apparatus. Nor do I limit myself to the particular apparatus shown, as the same may be modified as desired, so long as it will carry 80 out the methods covered by the claims.

In Figure 7, I have shown a slightly modified construction wherein the central pipe 30 is dispensed with and the lower end of the rotor mounted upon a stub bearing 53 formed on top of the chamber 34, said chamber being supplied with the liquid to be treated by a pipe 54 discharging directly thereinto and leading from the tank 4 of the regenerator 3. The discharge of gases is through a pipe 55 90 tapped centrally into the top of the cover 24, said pipe 55 leading to the suction pump 31.

Having thus fully described my invention, what I claim as new and desire to secure by Letters Patent, is:—

1. The method of pasteurizing liquids, which consists in subjecting the same, while circulating through a closed chamber, to a centrifugal action, subjecting the same to a heating medium, and simultaneously withdrawing therefrom through the center of the chamber, the deleterious gases therein.

2. The method of pasteurizing liquids and removing volatile matter therefrom, which comprises subjecting said liquids to a strong 105 centrifugal force to form a central space void of liquid, heating the liquids to a pasteurizing temperature and simultaneously permanently removing the volatile matter from the liquids by means of suction applied to said central 110 space.

3. The method of pasteurizing liquids, which comprises subjecting the liquids in a closed chamber to a sufficiently strong 115 centrifugal action to cause said liquids to rise up on the side walls of said chamber, raising the temperature of the liquids to effect pasteurization by means of a heating fluid under pressure, and withdrawing deleterious gases centrally from said chamber by means of suc- 120 tion.

In testimony whereof I hereunto affix my signature.

AAGE JENSEN.
